UNITED STATES PATENT OFFICE.

JOSEPH DE SUSINI-RUISECO, OF HAVANA, CUBA, ASSIGNOR TO FRANCIS S. KINNEY, OF NEW YORK, N. Y.

FLAME-GUARD.

SPECIFICATION forming part of Letters Patent No. 268,639, dated December 5, 1882.

Application filed October 24, 1881. Renewed October 6, 1882. (No model.)

To all whom it may concern:

Be it known that I, JOSEPH DE SUSINI-RUISECO, a subject of the Queen of England, residing in the city of Havana, Cuba, have invented certain new and useful Improvements in Flame-Guards, fully described and represented in the following specification and the accompanying drawings, forming a part of the same.

10 Previous to my invention great inconvenience was occasioned in the use of matches in lighting cigars, cigarettes, &c., by air-currents and wind blowing out the flame of the match before the cigar, cigarette, &c., was fairly lighted.

15 The object of my invention is to avoid this inconvenience, and to provide means whereby the flame of a match may be readily protected from such wind and air-currents; and it consists in a guard adapted to protect the flame of a match 20 from air-currents and wind while a cigar, cigarette, &c., is being lighted, which guard is provided with means for attaching it to a match box or case, and is capable of being detached from such box or case.

25 In the drawings accompanying this specification, Figure 1 represents a perspective view of one form of my invention, showing the guard open. Fig. 2 is a perspective view of the same, it being folded up. Fig. 3 is a perspective view 30 of the flame-guard attached to a match-case, the said guard being open. Fig. 4 is a sectional elevation of the same; and Fig. 5 is an elevation of a modified form of the mode of attaching the guard to a match-case.

35 A represents a flame-guard, rectangular in form and composed of sides—as 2, 6, 7, and 8—which are connected together in such a manner as to enable the guard to be folded up.

When it is desired to fold this flame-guard 40 up into small compass, so that it can be easily carried in the pocket of the user, the sides 6 and 7 are pressed inward, so that the side 6 will come in contact with the side 2 and the side 7 with the side 8, as is represented in dotted lines in Fig. 1. This done, the side 6, and with it the side 2, is pressed in contact with the side 7, as is clearly shown in Fig. 2. To enable this folding up of the guard the juncture of the sides 2, 6, 7, and 8 forms hinges, upon which they 45 turn. These, when the guard is composed of paper, card-board, or other fibrous material,

need be nothing more than a crease or a curve between the sides; but in the use of metal in forming the guard each side will be provided with short knuckles and spaces, and secured together by a pintle in a manner well known. 55

It is desirable in the use of this flame-guard that it should be in close connection with a match-case, so that in lighting a match, and with it a cigar, cigarette, &c., the inconvenience 60 of having to use two separate contrivances is not occasioned. I have therefore provided the flame-guard with a short tongue or hook, B, which projects from one of the sides, as 8, which tongue or hook may be inserted in a narrow opening provided in the side of the match-case, and be entirely with the match-case, as is shown in Figs. 3 and 4, so that the guard and the case may be carried together, and in lighting a match the former can be readily used to protect 65 the flame of the same. This flame-guard may be attached to a match-case in any convenient manner, the mode of attachment being varied to suit 70 the style of match-case with which it is to be connected. This tongue or hook B may enter a slot in the side of a match-case, as in Fig. 5, or the flame-guard may be provided with a spring-jaw, as 4, (represented in dotted lines at Fig. 4,) that will firmly clasp either 75 the bottom or sides of the match-case, or both. 80

The flame-guard A may be composed of any suitable material—such as paper, pasteboard, or sheet metal—and when composed of paper or pasteboard be saturated with a non-combustible material, so that it may not accidentally catch fire from the lighted match. Furthermore, one or all of its inside or outside surfaces may be made of a sandy or rough nature, to enable the striking of a match thereon to ignite it, or with the same material as 85 the parlor-matches, which ignite only by rubbing on the side of the box holding them.

I do not claim broadly all folding or collapsible structures capable of protecting a flame from air-currents, as I am aware that lanterns 90 have been made so as to be capable of collapsing, and that such structures have contained match-receptacles. Neither do I herein claim a match box or case provided with a folding flame-guard, as this latter subject-matter is 95 claimed by me in another application for United States Letters Patent; but 100

What I claim, and desire to secure by Letters Patent, is—

1. A flame-guard provided with means for attaching it to and detaching it from a match case or box, substantially as described.
2. A match case or box provided with a detachable flame-guard, substantially as described.

In testimony whereof I have hereunto set my hand in the presence of two subscribing witnesses.

JOSEPH DE SUSINI-RUISECO.
